UNITED STATES PATENT OFFICE.

GEORGE W. DRUHE, OF OAKLAND, CALIFORNIA.

PHOTOGRAPHIC-PRINTING FRAME.

1,072,215.

Specification of Letters Patent.

Patented Sept. 2, 1913.

Application filed December 4, 1912. Serial No. 734,901.

To all whom it may concern:

Be it known that I, GEORGE W. DRUHE, a citizen of the United States, residing at Oakland, in the county of Alameda and 5 State of California, have invented new and useful Improvements in Photographic Printing Frames, of which the following is a specification.

This invention relates generally to an improvement in photographic printing frames and particularly to a construction in the use of which any sized mat for a negative may be readily arranged in a simple and convenient manner.

15 The main object of the present invention is the provision of a printing frame and mat strips to coöperate therewith, the frame being arranged to permit the mat strips to be clamped in such related positions with 20 each other and with the negative as to form any size mat for the negative within the limits of the frame.

The invention in its preferred form of details will be described in the following 25 specification, reference being had to the accompanying drawings, in which:

Figure 1 is a plan view of the improved printing frame. Fig. 2 is an end elevation thereof. Fig. 3 is a section on line 3—3 of Fig. 1.

Referring particularly to the accompanying drawings, my improved printing frame comprises two rectangular skeleton frames hereinafter designated as the upper frame 1 and the lower frame 2. These frames are arranged in superimposed relation and maintained spaced by corner blocks 4 thereby providing channels or spaces 5 between the proximate surfaces of the upper and 35 lower frames throughout their lengths and widths except at the corner blocks. The lower frame is formed throughout its inner edge with an inward extension 6 rabbeted at 7 throughout its upper surface to receive 40 the usual glass 8 of the printing frame, the depth of the rabbet corresponding approximately to the thickness of the glass used. The upper frame is formed throughout the end and side pieces with longitudinally disposed channels extending vertically through 45 the end and side pieces, the lower ends of the channels being laterally enlarged in both directions to form receiving grooves 10 of increased width as compared with the chan- 50 nels.

As thus described it will be noted that the

channels centrally overlie the upper surfaces of the side and end pieces of the lower frame, it being understood that the walls 11 and 12 of the channels 5, which walls are formed by the lower surface of the upper frame bars and by the upper surfaces of the lower frame bars are in parallelism. Slidably mounted in the channels 9 are what I term 60 clamp members 13, said members constituting clamp plates 14 which are of appreciable width and a length corresponding to the width of the upper surface 12 of the frame bars of the lower frame. The clamp members also include lifting bars 15 which are 65 designed to slidably operate in the slots 9, springs 16 encircling said bars and fitting in the enlarged guide grooves 10 at one end and at the opposite end bearing on the clamp plates. As thus arranged the clamp 70 members are normally held with their clamp plates 14 in engagement with the upper surfaces of the frame bars of the lower frame by the tension of the spring 16, said clamp members being adjustable longitudinally to 75 any position of a particular frame bar through the medium of the lifting bars 15, it being obvious that by an upward pull 80 on the lifting bar the plate 14 may be lifted from the surface of the lower frame bar 85 and the clamp member then moved longitudinally in the guide slot 9 to any desired position. One clamp member is used preferably in each slot 9 though I contemplate the use of any number should such be found 90 desirable. The usual clamping back 17 is provided for the frame fitting within the upper frame bars and bearing on the glass, being held by the usual spring strips 18 and hooked projections 19, the latter being properly secured on the upper frame, as shown. 95

In connection with the improved printing frame I use mat strips 20, preferably right angled sections of opaque material having each arm graduated, as shown. In 100 use the negative is laid upon the glass in the usual manner. The mat strips are then placed in position being introduced through the channels so that one arm of each strip will project through the channel formed by 105 the end pieces of the frames and the other arm of each strip projecting through the channels formed by the side pieces of the frames. The strips are arranged in opposing relation as shown so that their respective arms intersect. The strips are now ad- 110 justed by means of their graduations to

form a mat of the desired size, accuracy and alinement being maintained through the graduations so that corresponding arms of the respective mat strips will register with the same graduations on the opposing arms. After this adjustment the clamp members are moved longitudinally of their guide slots until positioned above the particular arm of the mat strip and upon being released will clamp the mat strip in position. This clamping operation being effected for all four arms of the mat strip it will be noted that not only are the mat strips held in adjusted position but the negative underlying said strips is also held against accidental moving when applying the printing paper. The printing paper being then applied in the usual manner the back is secured in place and the printing 20 operation carried out.

It will be noted that a mat of any desired size limited only by the size of the frame being used can be secured as the particular strips may be of any width and need not necessarily be right angled strips but can be arranged in different forms to secure different effects, the sole requirement in this particular being that the mat strips be so constructed that they may be clamped 30 in place against accidental movement after being arranged to provide the desired mat.

What is claimed is:—

1. The combination with a printing frame, of mat strips comprising angularly related arms, and means carried by the frame for clamping the respective arms to maintain the mat strips in adjusted relation to provide mats of different sizes.

2. A printing frame including an upper and lower frame maintained in spaced relation to provide channels, the upper frame

being formed with guide slots overlying the surface of the lower frame, clamp members operable in the guide slots and coöoperating with the upper surface of the lower frame, 45 and mat strips wholly free of connection with the frame and adapted to be engaged by the clamp member.

3. A printing frame including two rectangular frames maintained in spaced relation to provide intervening channels, the upper frame being formed with longitudinally disposed slots in the sides and ends thereof overlying the lower frame, clamp members including clamping plates and lifting bars slidably positioned in said slots, 55 said plates being adapted to bear on the upper surface of the lower frame, and mat strips wholly free of connection with the frame and adapted to be engaged by said 60 plates.

4. A printing frame including two rectangular frames maintained in spaced relation to provide intervening channels, the upper frame being formed with longitudinally disposed slots in the sides and ends thereof overlying the lower frame, clamp members including clamping plates and lifting bars slidably positioned in said slots, 65 said plates being adapted to bear on the upper surface of the lower frame, springs 70 for maintaining clamping coöperation between said clamp plates and frame surface, and mat strips wholly free of connection with the frame and adapted to be engaged 75 by the plates.

In testimony whereof I affix my signature in presence of two witnesses.

GEORGE W. DRUHE.
